UNITED STATES PATENT OFFICE.

GEORGE FRASER, OF LEVEN, SCOTLAND.

POWER HAMMER.

Application filed March 10, 1922. Serial No. 542,713.

To all whom it may concern:

Be it known that I, GEORGE FRASER, a citizen of the United Kingdom of Great Britain and Ireland, and resident of Parkhill Smithy, Park Wynd, Leven, Fife, Scotland, have invented certain new and useful Improvements in and Relating to Power Hammers, of which the following is a specification, such as will enable others skilled in the art to which it appertains to make and use the same.

This invention relates to power hammers of that type in which the hammer is driven from a crank the shaft of which can be coupled to and uncoupled from the driving agent by a gear controlled from a foot lever.

In my machine the drive of the said shaft is obtained by friction between a driven wheel or drum on it and a driving wheel or drum on another shaft said wheels or drums being preferably multi-grooved on their faces or otherwise constructed so as to ensure a sufficient grip.

A band brake is fitted over the driven wheel to the shaft of which the crank of the hammer is attached, or the brake may be over a separate wheel or pulley on the said shaft. This brake is normally in contact with the driven wheel or pulley which is then stationary with the driving wheel out of contact. The band brake is connected, preferably adjustably, by a rod to a foot lever and held down by a spring in such a manner that when the lever is depressed the brake is lifted and the driving wheel contacts with the driven wheel and thus a friction drive between the two is made. The hammer may be adjustably connected to the crank and obviously the driving shaft may have fast and loose pulleys with striking gear or other means for entirely stopping the machine when so required.

My invention is shown by way of example in the accompanying drawings in which:—

Fig. 1 is a side view of the machine.

Fig. 2 is a back view of the same machine and

Figs. 3 and 4 show the wheels in and out of contact respectively, it being understood that very little movement from one position to the other is all that is necessary.

In this example the machine comprises a pedestal 1 on the upper part of which a shaft 2 carrying the driven grooved wheel 3 is fitted. The same shaft carries a disc 4 with

an eccentric 4^a to which the rod 5 of the hammer 6 is connected, the said rod being adjustable at 7. The support or anvil 8 is positioned below the hammer.

Parallel with shaft 2 is a second shaft 9 carrying the driving grooved wheel 10 which frictionally engages the wheel 3, said wheels being normally out of contact. A driving pulley 11 is mounted on the shaft 9 and conveys motion thereto from a belt, not shown.

A band brake 13 is placed over the driven wheel 3 and is connected to a rod 14 which is held down by a spring 14^a to normally keep the brake in contact with the wheel. This rod is adjustably connected to a foot lever 15 pivoted at 16. Assuming the machine to be running idle the motion of the shaft 9 is confined to the wheel 10 but immediately this wheel is raised into contact with wheel 3 the shaft 2 is rotated and the disc with crank 4^a rotates and by the rod 5 reciprocates the hammer 6. Thus when a workpiece is placed under the hammer the treadle or lever 15 is depressed and the brake 13 is lifted by rod 14 from the wheel 3 and at the same time the wheel 10 is raised into contact with the wheel 3 and power from the pulley 11 is communicated by shaft 9, wheels 10 and 3, eccentric 4^a and rod 5 to the hammer, causing it to strike the workpiece as long as the treadle is held down.

In Figs. 3 and 4 preferred forms of mounting the brake and the wheel 10 are shown. The brake is fixed at 17 and adjustably connected to the rod 14 at 18. This rod is held in clamp 19 of arm 20 which is secured to sleeves 21 in brackets 22 and carries the shaft 9. This shaft is eccentrically mounted in the sleeves 21 with the effect that when the arm 20 rises the sleeves have slight turning movement and lift the shaft 9 sufficiently to bring the wheel 10 into frictional engagement with wheel 3. The arm 20 is connected to spring 14^a the tendency of which is to pull down the arm and thus disengage the wheel 10 from wheel 3 and apply the brake.

What I claim is:—

1. A power hammer operating means comprising a pedestal, two parallel shafts on the pedestal, a driving wheel on one shaft and a driven wheel on the other shaft, treadle-operated means for shifting the shaft carrying the driving wheel, a spring to shift

the shaft when the treadle is not operated, and means on the shaft of the driven wheel for operating a hammer.

2. A power hammer operating means comprising a pedestal, two parallel shafts on the pedestal, a driving wheel on one shaft and a driven wheel on the other shaft, treadle-operated means for shifting the shaft carrying the driving wheel, a spring to shift the shaft 10 when the treadle is not operated, a band brake over the driven wheel adapted to be lifted by the actuation of the treadle and to be applied by the spring, and means on the shaft of the driven wheel for operating a 15 hammer.

3. A power hammer operating means comprising a pedestal, a shaft mounted on the pedestal, a driven wheel on the shaft, pivoted arms carrying sleeves capable of rotation in brackets mounted on the pedestal, a second shaft eccentrically mounted in the sleeves, a driving wheel mounted on the second shaft, a rod connected to the arms, a treadle connected to the rod and adapted to 20 shift the arms in one direction to bring the said two wheels into frictional engagement, a spring adapted to shift the arms in the opposite direction when the treadle is released, 25

and means on the shaft of the driven wheel for operating a hammer.

4. A power hammer operating means comprising a pedestal, a shaft mounted on the pedestal, a driven wheel on the shaft, pivoted arms carrying sleeves capable of rotation in brackets mounted on the pedestal, a second shaft eccentrically mounted in the sleeves, a driving pulley mounted on the second shaft, a rod connected to the arms, a treadle connected to the rod and adapted to shift the arms in one direction to bring the two said wheels 30 into frictional engagement, a spring adapted to shift the arms in the opposite direction when the treadle is released, a brake connected to the rod and adapted to be removed when the treadle is actuated and to be 35 applied by the spring acting through the rod when the treadle is released, and means on the shaft of the driven wheel for operating a hammer.

In witness whereof I have hereunto set my 40 hand in presence of two witnesses.

GEORGE FRASER.
